UNITED STATES PATENT OFFICE

2,376,921

TOY SUBMACHINE GUN

William J. Kelly, West Springfield, Mass.

Application May 15, 1944, Serial No. 535,671

6 Claims. (Cl. 46—191)

This invention relates to a toy sub-machine gun characterized by unique features of refinement expressly constructed in accordance with the principles of the instant invention and properly coordinated to provide an enlightening and thrilling toy for juveniles.

As implied by way of the preceding introductory statement of the invention, I am generally conversant with different types of toy-guns, and full well appreciate that these are of many and varied forms. Then too, I am aware that such toy-guns, including sub-machine forms have been evolved and produced to embody trigger-controlled percussion mechanisms. However, and notwithstanding the already existing state of the art, I have devised what is believed to be an innovation in this line of endeavor, the gun being, with the exception of a few parts, of all-wood construction, this in keeping with the requirements of the day necessitating the use of non-critical materials in production of various articles of manufacture.

More specifically, and in carrying out the principles of the invention, the toy-gun with which we are here concerned is possessed of unusual simplicity and durability and while possessing a construction which is a replica of a real sub-machine gun, embodies an ingenious noise-making device which when skilfully actuated produces the desired intermittent reports with time-controlled accuracy.

Although novelty may be predicated upon other parts, the phase of chief distinction and importance is the dummy magazine and trip-hammer mechanism incorporated therein and associated therewith to produce the desired intermittent results desired.

Other features and advantages will become more readily apparent from the following description and the accompanying illustrative drawings.

In the drawings, wherein like numerals are employed to designate like parts throughout the same:

Figure 1 is a side elevational view of a toy-type sub-machine gun constructed in accordance with the principles of the present invention.

Figure 2 is a top plan view of the same.

Figure 3 is a central longitudinal sectional view.

Figure 4 is a front end elevational view.

Figure 5 is an enlarged fragmentary detail section emphasizing and stressing the essence of the invention, namely, the percussion device or mechanism.

Figure 6 is a perspective view of an alternate

type of magazine which may, if desired, be utilized.

Referring now to the drawings by distinguishing reference numerals it will be seen that the main body, which is of wood, is denoted by the numeral 7 and is constructed to represent, at the left, the receiver, and at the right, the actuator 8. The conventionally shaped stock 9 is screwed or otherwise fastened to the rear or inner end of 10 said body 7. Also, at this point a disk held in place by a nail 10 represents the spring pilot. The actuator end 8 is formed with a socket and a solid wooden stick 11 is fitted and fastened therein, the top of the stick being milled as at 12 13 to provide an imitation barrel. The outer end of the stick is fashioned with a head 13 forming the front sight, this carrying the projecting compensator 14. A rectangular block 15 is fastened to the intermediate portion of the barrel and 20 serves as a base for a laterally depending properly angled and shaped front grip 16. A special adapter block 17 serves as a mount for the rear grip 18 (see Figure 5). The adapter is fastened to the body 7 and is fashioned into a trigger guard 19 with a finger-slot 20. This part is hollowed out to provide a slideway for a slide block 21 having a finger opening 22, said block coacting with the trigger guard in forming a squeeze-type trigger.

30 The dummy magazine is denoted at 23 and is suitably fastened on the adapter and connected with the body and this is of hollow wooden construction. The main shell 24 is provided with a wooden lid or cover 25, this being the impact diaphragm or plate. The parts 24 and 25 provide a noise amplifying or resounding box. On its inner face the cover is provided with a leaf spring 26 carrying a clapper 27 which is in effect a knocker. A dowel pin 28 is connected at its rear end to the trigger slide 21 and is suitably connected at its forward end with the intermediate portion of the return and clapper actuating spring 26.

45 For further ornamentation and proper imitation a suitable rear sight 29 is mounted atop the rear or inner end of the receiver or body 7.

The finished gun is properly painted with predetermined parts black and mahogany to afford the desired realistic over-all appearance. The user is thus familiarized with the appearance and proportions of an actual sub-machine gun. The complete structure is sturdy, not likely to get out of order, comparatively simple and yet extremely light in weight. It is in every sense of the word an imitation gun of the type specified.

It is obvious that the intermittent trip-hammer noises resembling successive reports of a machine-gun is produced by successively squeezing and releasing the trigger 21 in relation to the grip 18 and trigger guard. The user simply allows the tip of the finger to slip out of the finger opening or hole 22 and by skilfully achieving this aim, reports of desired rapidity are thus produced.

Reference being had now to Figure 6 it will be seen that the numeral 30 denotes a hollow wooden rectangular box which is an alternative type of magazine which can be used instead of the circular type disclosed in the other views.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

Having described the invention, what is claimed as new is:

1. A wooden toy sub-machine gun of the class described comprising a body, a stock on the inner end of the body, a barrel on the outer end of the body, a depending front grip carried by the barrel, a depending rear grip carried by the body, a hollow wooden magazine, a trigger guard, a trigger slidably mounted in said trigger guard, a clapper in said magazine, and an operating connection between the clapper and trigger.

2. An imitation sub-machine toy gun of the class described comprising a body, a barrel, a stock connected to the body, front and rear hand-grips, the rear hand-grip including an adapter having a recessed trigger guard, a dummy magazine, a spring mounted in said magazine, a clapper on the free end of the spring, a slide shiftably mounted in the recessed adapter and having a finger-hole, said slide constituting a trigger, and an operating connection between the spring and trigger.

3. In a toy-gun construction of the class described, a grip including a trigger guard, a trigger slidably mounted in said trigger guard, a hollow wooden noise amplifying box representing a magazine, a spring-finger anchored at one end therein, a clapper on the free end of the spring

coacting with an adjacent wall of the box, a slide mounted in said trigger guard, and a dowel pin connection between the slide and spring.

4. As a component part of a toy wooden gun of the class described, an adapter block including a hand-grip, said adapter block being fashioned into a slotted recessed trigger guard, a hollow wooden box including a main shell portion and a cover therefor, said box representing a magazine, a spring-finger anchored at one end of the inner surface of the cover, a wooden clapper secured to the free end of the spring and contacting the inner surface of the cover, a rectangular slide shiftably mounted for reciprocation in said trigger guard and provided with a finger-hole constituting a trigger, a dowel pin slidable through the shell of the box and connected at one end to the trigger and at its opposite end to the intermediate portion of the spring.

5. A wooden toy sub-machine gun of the class described comprising an elongated body representing a receiver and actuator, said body being socketed at its inner end, a solid stick having its inner end telescopically fitted in said socket, said stick having a serrated upper surface and being provided at its outer end with a head representing a front sight, and an extension representing a compensator, the stick being solid and representing a barrel, a rear or inner sight on the inner end of said body, a stock mounted on the inner end of said body, a block secured to the intermediate portion of the stick, a hand-grip secured to and depending from said block, an adapter block secured to the intermediate portion of said body and including a grip, said adapter block being fashioned into a slotted recessed trigger guard, a wooden magazine secured to the frontal portion of said adapter block, noise making mechanism in said magazine, a trigger slidably in said trigger guard, and an operating connection between the trigger and noise making mechanism in said magazine.

6. All wood toy sub-machine gun of the class described comprising a body, a barrel, a stock connected to the body, front and rear hand grips, an imitation magazine, a spring mounted in said magazine, a clapper on the free end of the spring engageable with an adjacent wall of the magazine, a hand-operated slidably mounted trigger, and an operating connection between the spring and trigger.

WILLIAM J. KELLY.
